UNITED STATES PATENT OFFICE.

LEDRU R. WEBSTER, OF HOLLY, MICHIGAN.

HAME-TUG.

SPECIFICATION forming part of Letters Patent No. 413,694, dated October 29, 1889.

Application filed July 1, 1889. Serial No. 316,226. (No model.)

To all whom it may concern:

Be it known that I, LEDRU R. WEBSTER, a citizen of the United States, residing at Holly, in the county of Oakland and State of Michigan, have invented certain new and useful Improvements in Hame-Tugs, of which the following is a specification, reference being had therein to the accompanying drawings.

This invention relates to new and useful improvements in hame-tugs; and the invention consists in the peculiar construction of the various parts, whereby the article is produced economically, without stitching or the use of leather, while it is at the same time lighter, stronger, and as serviceable for use as the more expensive constructions in present use, all as more fully hereinafter described, and shown in the accompanying drawings, in which—

20 Figure 1 is a perspective view of my improved hame-tug. Fig. 2 is a longitudinal section thereof. Fig. 3 is a cross-section thereof on line $\alpha\alpha$ in Fig. 1.

My improved hame-tug consists of the sections A and B, hinged together. The front section or loop A is constructed of leather in the usual manner and provided with the hame-clip C, secured by a rivet D to the body of the loop. The section B consists of a strong 25 bar of wood E, substantially of rectangular cross-section, as shown in Fig. 3. Into the face of this bar a channel F is sunk of sufficient depth to receive the metal strap G, which has beveled edges G', and extends the whole 30 length of the bar around the ends, where it forms the eyes H and H', and some distance on the back, where it is also sunk into the bar. This strap is firmly secured to the bar E by means of rivets I, and a lining J, preferably of leather, is secured into each eye of the strap, the wooden bar being suitably cut 35 away at the ends to form the tongues K, which extend between the lining into the eyes, and thereby hold the lining in place. 40 Into the face of the bar are cut suitable notches to receive the cross-bars of the loops L, which are held in place by the metal strap. 45

The section A is hinged to the section B by means of a link or loop M, one cross-bar 50 of which engages into the eye N, formed in

the section A, and the other cross-bar into the eye H of the section B. To the eye H' on the rear end of the bar a suitable trace-buckle N' is secured. If desired, cross-rivets O may be secured transversely to the bar E 55 to prevent the wood from splitting. In practice, the parts being constructed and arranged as shown and described, they are intended to be used in the well-known manner to connect the forward end of the traces to 60 the loops.

The ends of the traces are in the usual manner adjustably secured to the trace-buckle N', (of which the part carried by the traces is not shown,) and the free end of the 65 trace is engaged into the loops L. The hame-clip C is engaged to the usual tug-hook on the hames.

It will be seen that my device is constructed with a minimum of leather without impairing the appearance, the latter being obtained by painting or finishing the bar E in imitation of leather. At the same time the durability, increased strength, lightness, and cheapness of my construction are decided advantages.

What I claim as my invention is—

A hame-tug composed of a front section or loop provided with a hame-clip and a rear section hinged thereto at the front end and 80 provided at the rear end with a suitable trace-buckle, said rear section comprising a bar of wood, a metallic strap sunk into the bar and bent around the ends thereof to form eyes for engaging the front end with the 85 cross-bar of a link which hinges it to the front section and for engaging the shank of the trace-buckle at the rear end, rivets securing the metallic strap to the bar, loops secured in notches of the bar by the metallic 90 strap, and a lining in each eye of said strap, all substantially as described.

In testimony whereof I affix my signature, in presence of two witnesses, this 8th day of May, 1889.

LEDRU R. WEBSTER.
